UNITED STATES PATENT OFFICE.

LOUIS JANSSENS, OF BRUSSELS, BELGIUM.

PERFORATING MECHANISM.

1,413,164.

Specification of Letters Patent. Patented Apr. 18, 1922.

Continuation in part of application Serial No. 760,281, filed April 10, 1913. This application filed May 22, 1914. Serial No. 840,255.

(GRANTED UNDER THE PROVISIONS OF THE ACT OF MARCH 3, 1921, 41 STAT. L., 1313.)

To all whom it may concern:

Be it known that I, LOUIS JANSSENS, a subject of the King of Belgium, resident at Brussels, 49 Rue du Pont Neuf, Belgium, have invented new and useful Improvements in Perforating Mechanism (for which I have filed applications in Belgium, May 28, November 11th, and December 3rd, 1912; Germany, April 2d, 1913; Italy, April 7th, 1913; 5 France, April 5th, 1913; Great Britain, April 1st, 1913; Holland, April 12th, 1913; Rumania, February 22, 1913; Spain, February 28, 1913; Switzerland, March 6, 1913; Denmark, March 3, 1913; Russia, March 21, 10 1913; Hungary, March 20, 1913; Austria, March 26, 1913; India, March 31, 1913; Canada, April 8, 1913; Australia, April 1st, 1913; Brazil, April 18, 1913; Argentina, April 25, 1913,) of which the following is a specification.

It is the object of the present invention to provide an apparatus for perforating a band on which notes of music are recorded in synchronism with the movement of a kinematographic film so that appropriate pieces of 15 music can be recorded and thereafter reproduced in synchronism with the pictures on the film as they are projected on a screen.

In order to achieve this result the musician 20 who must be well acquainted with the single scenes on the film will during a trial projection of the pictures on the film upon a screen, play on a musical instrument an improviso of a suitable music piece, the single notes or 25 tunes of which are recorded in the well known manner upon an endless note band.

It is the object of the present invention 30 to perforate this band in synchronism with the movement of the film band during the reproduction of the picture in order to make the same adapted to be moved synchronously with said film.

With this end in view the drum from 35 which the film is unrolling is closing an electric circuit at the end of each revolution energizing an electro-magnet which controls a perforating device producing upon each revolution of the film spool a perforation in the note band thus providing a means for 40 moving the band during the reproduction in synchronism with the film band and reproducing between each two perforations a

piece of music appropriate to the pictorial scenes shown in the screen.

In the accompanying drawing, a preferred form of apparatus is shown in side view and diagrammatically.

The film spool *a* carries in the well known manner the film band *b* and is provided with a laterally projecting pin *c*. A plate *d* upon 55 the base of the projecting apparatus carries at its upper end an insulating plate *e* and a contact screw *f* and at its opposite end a contact screw *f'*.

A flat contact spring *g* is secured with its 60 upper end to the contact screw *f* and to the plates *e* and *d*, while its lower end is normally kept at a distance from the contact screw *f'*. One pole of a battery *h* is connected by a wire *i* with the upper contact or pole 65 *f*, while its other pole is connected by a wire *i'* to an electro-magnet *t* which is also connected by means of a wire *i''* to the lower contact screw *f'*. The electro-magnet *t* forms part of a perforator comprising a 70 standard *k* to the upper bent arm of which the rear end of an arm *m* is pivotally secured at *l*, while the front end of said arm carries a contact plate *o* forming the armature of the electro-magnet *t*.

Intermediate its ends the arm *m* carries a perforating tool *n* and a spring *u* connecting the outer end of said arm to an arm *p* of the standard *k* tending to normally hold the armature *o* out of contact with the electro- 85 magnet *t* so that the perforating tool is also kept out of contact with the note band *r* upon the table *q* which underneath of said perforator is provided with an opening or hole *s*.

The note band *r* is moved across the table 90 step-by-step by means of any well known device not illustrated in the drawing.

The apparatus works in the following manner:

While during the normal position of rest 95 of the parts the circuit over the battery *h* is interrupted on account of the space separating the spring *g* from the contact *f'*, the contact spring *g* during the rotation of the film spool will be pressed towards the plate 100 *d* as soon as the projection *c* of the film spool during the rotation of the same comes into contact with said spring. Therefore, while said projection is pressing against the cen-

tral curved part of said spring contact will be made between the lower end of said spring and the contact screw f' thus closing a circuit over the electro-magnet t upon each 5 revolution of the film spool. By the energizing of the electro-magnet to attract the armature o and the outer end of the arm m so that the perforating tool n will at certain predetermined intervals perforate the note 10 band r advancing underneath of said tool over the hole s of the table q in a step-by-step movement. However, as soon as the pin or projection c has passed the curved central part of the spring g said spring will 15 turn into its initial position and the circuit will again be opened at the contact screw f' and will remain open until the film spool a has carried out one full revolution and then the pin c will again press the spring g 20 toward the plate e and close the circuit at the contact screw f' which operation will be successively repeated upon each full revolution of the drum or spool a .

In order to play such a perforated record 25 in absolute coincidence, as regards time, with the scenes on the film which follow one another, this latter is placed in the kinematograph and the music strip in the reproducing instrument in their respective starting 30 positions and then both instruments, the kinematograph and the piano are simultaneously started and their speed is automatically regulated by the synchronizing apparatus described in my co-pending application 35 No. 760,281, filed April 10, 1913, of which this application is a continuation in part. The reproducing apparatus described in this former application which is used in connection with the music strip in which 40 signs or perforations are marked by means of the recording device forming the object of the present invention, for maintaining synchronism during the reproduction, con-

sists of two movable members provided with needles or pointers, one of which is displaced 45 to a certain extent on the passage of a perforation on the music strip, while the other is displaced to a similar extent after a similar movement of the film has been executed. One of these members being provided with 50 an electric resistance, while the other is provided with an electric contact which is displaced on the resistance in either one direction or the other according to circumstance that one or the other member will lead or lag. 55 Thereby the supply of the current to the motors is regulated in such a manner as to speed the one which lags and to tamp the action of the one which is leading.

I declare that what I claim is:

1. A perforating device of the character described comprising in combination, a toothed drum over which passes a perforated kinematographic film, a shaft for said drum and means for automatically and synchronously perforating a music strip in harmony with the unwinding of the kinematographic film upon each revolution of the drum, substantially as described. 65

2. A perforating device of the character 70 described, comprising in combination, a toothed drum over which passes a perforated kinematographic film, a shaft for said drum, means on said shaft for closing an electric circuit at the end revolution of said drum, 75 and perforating members operated upon the closing of said contact for automatically and synchronously perforating the music strip in harmony with the unwinding of the kinematograph film, substantially as described. 80

In testimony whereof I affix my signature in presence of two witnesses.

LOUIS JANSSENS.
